UNITED STATES PATENT OFFICE.

THEODORE MUNZERT, OF ROCHESTER, NEW YORK.

RULING-MACHINE.

No. 918,076.

Specification of Letters Patent.

Patented April 13, 1909.

Application filed January 5, 1906, Serial No. 294,791. Renewed February 25, 1909. Serial No. 479,892.

To all whom it may concern:

Be it known that I, THEODORE MUNZERT, a citizen of the United States, and resident of Rochester, in the county of Monroe and State of New York, have invented certain new and useful Improvements in Ruling-Machines, of which the following is a specification.

This invention relates to ruling machines, 10 and consists in the device hereinafter described and claimed.

The object of the invention is to provide a striker apparatus for ruling machines that is capable of more accurate registry of the 15 ruling lines than in the devices heretofore in use.

In the drawings:—Figure 1 is a side elevation of a ruling machine embodying this invention; Fig. 2 is an enlarged perspective 20 view of the striker device of said ruling machine; Fig. 3 is a cross-section on the line 3—3 of Fig. 5, when the pens are in the lowered or ruling position; Fig. 4 is a cross-section on the same line of Fig. 5, when the pens 25 are raised or in the nonruling position; and Fig. 5 is a longitudinal section on the line 5—5 of Fig. 3 through the left hand end of the device, as shown in Fig. 2.

The ruling machine to which this device is 30 attached is of a usual type, having the frame 1, the upper belt 2 driven as usual and passing around the pulleys 3, 4, the retaining cords 5 passing around the pulleys 6, 7, 8, the cam wheel 9 driven in any suitable manner, such as by the gears 10, 11, 12, 13, from 35 a gear, not shown on the shaft of the pulley 3 so that the cam wheel 9 moves in correspondence with the belt 2.

The striker device is carried by standards 40 14 (of which only one is shown) and a cross bar 15 extending entirely across the machine over the belt 2. To the cross bar is fastened the curved plate 16, on which rests the ink holding fabric, such as the flannel 17, from 45 which extend the feeding strands 18 to the pens 19. The flannel 17 may be held in place by a clamping bar or plate 20 having means, such as the spring hooks 21, for engaging the edge of the bar 16. The bar 16 50 at each end has the depending plates 22, 22^a carrying the bearings or journals for the tilting striker bar. In the present case the striker bar consists of an upper metal plate 23, an intermediate plate 24 of softer material, such as wood, and a lower metal plate 55 25. Pens 19 are clamped between one of the

outer plates 23, 25 and the intermediate plate 24, and thumb screws 26, Figs. 3 and 4, clamp the three plates together for holding them in the clamping position. Dowel pins 60 27 may be employed, extending from one plate 23 into the other 24, for strengthening the clamping device thus formed, and for maintaining the relative positions of the parts thereof. The intermediate plate 24 65 may rest against the dowel pins 27, or the said dowel pins may pass through said intermediate plate. The three clamping plates rest upon a supporting bar 28 and are fastened to said supporting bar by thumb 70 screws 29 passing through slots 30, 30 in said supporting bar. The lower clamping plate 25 may have a lug 31 upon it that fits in said slot 30 and determines the exact relative positions of the two parts. On loosening 75 the thumb screws 29, the clamping device consisting of the bars 23, 24, 25, may be moved longitudinally upon the bar 28 through an opening in the plate 22^a, and thus a lateral adjustment of the pens with 80 reference to the belt 2 is provided.

The supporting bar 28 is journaled in the end plates 22 and 22^a, and inasmuch as the journals are the same at both ends only one journal is shown, as in Fig. 5. From the 85 plate 28 projects a stem 32 that carries a cone 33 running on screw threads on the stem. In the end plate 22 is the cup 34 forming with the cone 33 the race-way for the anti-friction balls 35. On the stem 32, is also fastened an 90 arm or lever 36 carrying a pin or roller 37 for engagement with the cams 38 on the cam wheel 9. The arm 36 and the plate 22 are connected by a spring 39 which may be, as shown in the present case, coiled around the 95 cone 33 with one end attached to the plate 22 and the other end attached to the arm 36. As the plate 22 is stationary, the spring returns the arm and the striker device to the normal or ruling position shown in Fig. 3. 100 When the cams 38 tilt the arm 36, the striker device is tilted and the pens are lifted from the surface to be ruled in accordance with the setting of said cams.

The stem 32 in the present case is formed 105 on a separate block 40 that is fastened to the supporting bar 28 in any suitable way, such as by screws 41.

In order not to complicate the drawings and description in the present case, no gate 110 is shown upon the ruling machine, although one may be used or not, as desired.

The operation of the device is as follows:— After the pens are properly fixed in place, having their rear ends attached between the intermediate bar 24 and one of the plates 23 or 25, the flannel is placed in position and the threads or feeding wicks to the separate pens, the machine is started and paper is fed into it and lines will be drawn upon said paper in accordance with the ink or inks supplied to the flannel. When a line is to be discontinued or to be begun, a cam 38 of the right length is placed in one of the cam grooves 42 of the cam wheel 9 and is fastened therein by a thumb screw or screws 43. As the operation of the machine continues, the paper blank 49, Fig. 2, is held down upon the belt 2 by the threads 5 and the ruling occurs. When a cam 38 acts upon the pin or roller 37, the striker device is tilted to the position shown in Fig. 4, the pens are thereby lifted from the paper and ruling stops. It will be noted that in this apparatus it is the clamping device only that is tilted, that the felt or flannel loaded with ink remains stationary upon the plate 16, and that the parts are so adjusted and balanced as to permit the tilting movement of the striker device to be easy and without shock or jar.

In order to produce a delicate adjustment of the angular position of the arm 36 upon the pin or stem 32, the said pin or stem carries a circular plate 44 fastened upon said stem in any suitable manner such as by the lock nut 45. The said plate 44 has peripheral bearing surfaces for two set screws. In the present instance these bearing surfaces are formed by a single flat surface 46, see Fig. 2. The arm 36 fits around the circular plate 44 and carries the set screws 47 situated at a suitable distance from each other, and having their inner ends abutting against the bearing surfaces at the ends of the single flat surface 46. By turning the set screws to such relative positions as may be found desirable, it is obvious that the angular position of the arm 36 may be delicately adjusted upon the pin or stem 32, and the action of a cam 38 through the arm 36 in moving the pens to and from the work can be very delicately adjusted.

What I claim is:—

1. In a striker device for ruling machines, a movable belt, a stationary bar extending across said belt and carrying a stationary flannel supporting plate, a pair of stationary bearing plates on the ends of the flannel supporting plate, clamping mechanism for the pens under said plate, having pivots at its ends in said bearing plates, an arm attached to said clamping plates for tilting the same, and a cam wheel for operating said arm.

2. In a striker device for ruling machines, a movable belt, a stationary bar extending across the belt and carrying a stationary flannel supporting plate, a pair of stationary

bearing plates, clamping plates for the pens having pivots in said bearing plates, a circular plate on one of said pivots and having peripheral bearing surfaces, an arm having a portion extending around said circular plate, 70 adjusting screws passing through said portion of the arm and against said bearing surfaces of the circular plate, and a cam wheel for operating said arm.

3. In a striker device for ruling machines, 75 a movable belt, a stationary bar extending across the belt and carrying at one side a stationary flannel supporting plate, a pair of stationary bearing plates secured to the ends of said flannel supporting plate, clamping 80 plates for the pens lying under said supporting plate and having pivots in said bearing plates, a spring for turning said clamping plates in one direction with reference to the bearings, an arm attached to said clamping 85 plates for tilting the same, and a cam wheel for operating said arm.

4. In a ruling machine, a flannel supporting plate having depending bearings at its ends provided on their outer faces with cups 90 or ball races, a rocking pen bar under said plate and having journals at its ends mounted in said bearings and provided with conical nuts, balls between said conical nuts and races, and a pen mechanism adjustable on 95 said rocking bar.

5. The combination with the pen clamp, of a longitudinally slotted rocking bar upon which said clamp rests and slides in the direction of its length, and thumb screws extending up through the slot in the bar into threaded openings in the lower side of the clamp.

6. A pen clamp comprising a pair of metallic plates, dowel pins between the rear 105 portions of the plates, an intermediate non-metallic plate between which and the metallic plates the pens are to be clamped, and thumb screws extending through all three plates.

7. A pen clamping mechanism comprising a pair of metallic plates, the lower one of which has threaded apertures, an intermediate non-metallic plate between which and the metallic plates the pens are to be clamped, thumb screws extending through all three plates, a longitudinally slotted rocking bar upon which said plates rest, and thumb screws extending up through said longitudinal slot into the threaded apertures 115 in the lower metallic plate.

8. The combination with the side bearings one of which has an enlarged opening, of a rocking bar journaled at its ends in said bearings, and a pen clamp adjustable longitudinally upon said bar and through the opening in said bearing.

9. The combination with stationary side bearings one of which has an enlarged opening, and a stationary downwardly curved or 130

inclined flannel supporting plate, of a rocking bar journaled in said side bearings below the flannel supporting plate and a pen clamp adjustable longitudinally on said rocking bar 5 through the opening in the bearing.

10. The combination with the stationary flannel supporting plate, of the rocking pen clamp therebelow, having end journals, side bearings for the said journals, cones on the 10 journals, balls between the cones and side bearings, a spring for rocking the pen clamp in one direction and a lever by which the clamp is rocked to lift the pens.

11. In a striker device for ruling machines, 15 clamping plates for the pens, pivot stems ex-

tending therefrom, supports for said pivot stems, a circular plate upon one of said pivot stems having peripheral bearing surfaces, an arm having a portion fitting around said circular plate, a pair of set screws passing 20 through the last mentioned portion of said arm and bearing against said bearing surfaces for adjusting the angular position of said arm with reference to said pivot stem, and a cam wheel for operating said arm.
